ASHTRAY

Donald J. O'Connor, 65 Bissell St.,
East Hartford, Conn. 06108

Filed Dec. 5, 1968, Ser. No. 14,795

Term of patent 14 years

Int. Cl. D27—03

U.S. Cl. D85—2

FIG. 1 is a top plan view of an ashtray embodying the present design.

FIG. 2 is a bottom view of the ashtray of FIG. 1.

FIG. 3 is a vertical sectional view taken on the line 3—3 of FIG. 1.

FIG. 4 is a vertical sectional view taken on the line 4—4 of FIG. 1.

I claim:

The ornamental design for an ashtray, as shown and described.
